UNITED STATES PATENT OFFICE.

KNUT M. DAHL, OF SAN FRANCISCO, CALIFORNIA, ASSIGNOR TO UNION IRON WORKS CO., OF SAN FRANCISCO, CALIFORNIA, A CORPORATION OF CALIFORNIA.

LIQUID-ATOMIZER.

1,008,119.

Specification of Letters Patent. Patented Nov. 7, 1911.

Application filed June 12, 1911. Serial No. 632,711.

To all whom it may concern:

Be it known that I, KNUT M. DAHL, a citizen of the United States, residing in the city and county of San Francisco, State of California, have invented a new and useful 5 Liquid-Atomizer, of which the following is a specification.

The object of my present invention is to devise a novel atomizer wherein liquids such 10 as crude oil, water or any other desired liquid, may be atomized and wherein the only agent employed for this atomization is the pressure of the liquid.

With the above end in view, my invention 15 consists of a novel construction of a liquid atomizer.

It further consists of a novel construction and combination of a holder, an atomizer disk, a tip and novel means for securing 20 the parts in assembled position.

It further consists of other novel features of construction, all as will be hereinafter fully set forth.

For the purpose of illustrating my invention, I have shown in the accompanying drawings one form thereof which is at present preferred by me, since the same has been found in practice to give satisfactory and reliable results, although it is to be 25 understood that the various instrumentalities of which my invention consists can be variously arranged and organized and that my invention is not limited to the precise arrangement and organization of these instrumentalities as herein shown and described.

Figure 1 represents a sectional elevation of a liquid atomizer embodying my invention. Fig. 2 represents a sectional elevation 40 of the tip in detached position. Fig. 3 represents a sectional elevation of the atomizer disk in detached position. Fig. 4 represents a plan view of the atomizing disk.

Similar numerals of reference indicate 45 responding parts in the figures.

Referring to the drawings:—1 designates a body or holder to which is removably secured a conduit 2, which, in the present instance, has one end threaded as indicated at 50 3, thereby adapting the same to engage with the threaded walls 4 of the holder 1, said conduit 2 communicating with a source of liquid supply which is to be atomized, it being understood that the liquid passing 55 through the conduit 2 is under a desired

pressure. The holder 1 is provided with an internal bore 5, the outer end of which is flared outwardly or beveled or inclined as indicated at 6. The end of the holder 1 is exteriorly threaded as indicated at 7, thereby adapting the same to receive a clamping nut 8, which latter is provided with an inwardly projecting flange 9.

10 designates an atomizer disk which is provided with a rearward extension 11 having a cylindrical contour in the present instance and which, when the parts are assembled position, is adapted to extend into the bore 5 a desired distance. The disk 10 is provided with a laterally extending annular flange 12 which is provided with one or more apertures 13, it being understood that the inner face of the flange 12 is adapted to seat against the end of the holder 1, which is faced off as indicated at 14. The front face of the disk 10 is provided with an extension 15 in the shape of a cone.

16 designates one or more ports or passages which extend tangentially from a port 13 to the cone 15, it being best seen 30 from Fig. 3 that at the base of the cone there is an annular groove 17 which extends slightly into the front face of the flange 12.

18 designates a tip which is provided at its rear end with a lateral extending flange 35 19 which is adapted to close the front end of the ports 13 when the parts are in assembled position, the forward end of the tip 18 being adapted to pass through the flange 9 of the clamping nut 8. The tip 18 is internally recessed as indicated at 20 in such

a manner that the recess is given the form of a cone which communicates with an outlet or discharge port 21 extending through the forward end of the tip. The walls of the discharge port 21 are angularly inclined to the walls of the conical recess 20. In order to assemble the parts, the atomizer disk 10 is placed on the end of the holder 1, the tip 18 is then placed upon the disk 10 40 and the clamping nut 8 is secured in position so that the shoulder 22 formed by the flange 9 of said clamping nut 8 will engage the flange 19 of the tip 18 and thereby cause the tip 18 and the atomizing disk 10 to be 45 secured in assembled position with respect to the holder 1.

The operation of my novel atomizer will now be apparent and is as follows:—The liquid under pressure entering through the 50

conduit 2 passes into the chamber formed by the bora 5 thence to the ports 3 and through the passages 16 so that the liquid passes tangentially to the cone 15, thereby causing the liquid to receive a rotary, whirling or centrifugal motion as it passes through the conical passage 23 and the discharge port 21 of the tip 18, and owing to the centrifugal force the liquid is discharged in the form of a fine spray, as is evident.

It will be apparent to those skilled in this art that when it is desired to inspect the disk 10 or remove the tip 18, this may be readily accomplished by removing the clamping nut 8 whereupon all the parts are accessible for the purpose of cleaning, inspection or repairs.

In so far as I am aware, I am the first in the art to devise an atomizer wherein the liquid is forced under pressure tangentially against a cone so that as it passes from the tip of the atomizer there is imparted thereto a rotary, whirling or centrifugal motion of the character described so that the centrifugal force will cause the liquid to be ejected from the discharge port in the form of a fine spray, and it is to be understood that my claims to such features are to be interpreted with corresponding scope.

The number of ports 13 and 16 employed will vary in accordance with the conditions and requirements met with in practice.

It will now be apparent that I have devised a novel and useful construction of a liquid atomizer which embodies the features of advantage enumerated as desirable in the statement of the invention and the above description, and while I have, in the present instance, shown and described a preferred embodiment thereof which has been found in practice to give satisfactory and reliable results, it is to be understood that the same is susceptible of modification in various particulars without departing from the spirit or scope of the invention or sacrificing any of its advantages.

Having thus described my invention, what I claim as new and desire to secure by Letters Patent, is:—

1. A nozzle comprising a body with an

exit, a disk overlying said body and having a passage communicating with said exit, a tip overlying said disk and covering a portion of said passage and provided with a conical recess and with a discharge port leading from said recess, the covered portion of said passage entering said recess tangentially, and means for uniting the recited parts.

2. A nozzle comprising a body with a flaring exit, a disk overlying said body and provided with a cone and having a passage communicating with said exit, a tip overlying said disk and covering a portion of said passage and provided with a conical recess receiving said cone and with a discharge port leading from said recess, the covered portion of said passage entering said recess tangentially, and means for uniting the recited parts.

3. In a device of the character described, a nozzle comprising a body with a flaring exit 6, a disk 10 overlying said body and provided with a rearward extension 11, a cone 15, apertures 13, and passages 16 extending tangentially to said cone and terminating in proximity thereto, a tip 18 overlying said disk and covering a portion of said passages and provided with a conical recess 20 receiving said cone, and a discharge port leading from said recess, and means for uniting the recited parts.

4. In an atomizer, a body having an inlet thereto, a disk at one end of said body and having a port 13 connecting with said inlet, said disk having a cone at its forward end and a passage 16 tangential to said cone and communicating with said port, said disk having near the base of said cone an annular groove 17 also communicating with said passage 16, a tip having a discharge port and a conical shaped recess in communication therewith into which said cone extends, and means for rigidly securing said tip, disk and body in assembled position.

KNUT M. DAHL.
